UNITED STATES PATENT OFFICE

ANNE M. BOEVER, OF CAMBRIDGE, MASSACHUSETTS, ASSIGNOR TO THE SILEX COMPANY, A CORPORATION OF CONNECTICUT

DESIGN FOR AN UPPER BOWL FOR COFFEE MAKERS

Application filed July 16, 1928. Serial No. 27,493. Term of patent 14 years.

To all whom it may concern:

Be it known that I, ANNE M. BOEVER, a citizen of the United States, residing at Cambridge, in the county of Middlesex and State of Massachusetts, have invented a certain new, original, and ornamental Design for Upper Bowls for Coffee Makers, of which the following is a specification, reference being had to the accompanying drawings, forming part thereof.

In these drawings,—

Fig. 2 is a plan view of one half of the same.

I claim:—

The ornamental design for an upper bowl for coffee makers, substantially as shown.

In testimony whereof I affix my signature
ANNE M. BOEVER.
